DESIGN FOR A RUG

Alfred V. Fago, New York, N. Y., assignor to Bigelow-Sanford Carpet Co., Inc., a corporation of Massachusetts

Application November 22, 1934, Serial No. 54,115

Term of patent 7 years

To all whom it may concern:

Be it known that I, Alfred V. Fago, a citizen of the United States, and resident of New York, in Bronx County, and State of New York, have invented a new, original, and ornamental Design for a Rug, of which the following is a specification, reference being had to the accompanying drawing forming part thereof, in which a plan view of the rug is shown.

The lining and stippling represent contrasting colors, or contrasting tones of the same color.

I claim:

The ornamental design for a rug, substantially as shown and described.

ALFRED V. FAGO.
